SEPARABLE ARTICLE OF JEWELRY

John Fielding, North Providence, R. I.; Union Trust Company, executors of said John Fielding, deceased; said Fielding and said executors assignors to Joseph P. Whitaker, Apponaug, R. I.

Application July 12, 1937, Serial No. 153,153

11 Claims. (CL. 63—20)

This invention relates to an article of jewelry which has separable parts, and particularly to a brooch comprising a plurality of clips mounted on a frame part and detachably secured thereto.

5 An object of the invention is to provide simple and effective means for securing a plurality of clips to a frame member which will be effective regardless of the relative size or width of the clip and the frame whereby a variety of sizes may be 10 attached to the same frame member.

Another object of the invention is to provide a locking device which will lock out of working position so that the locking device will positively not interfere when the parts are assembled but 15 may thereafter be moved to securing position.

Another object of the invention is to provide a simple and effective locating means which will serve in cooperation with the locking device to hold the parts firmly and securely together 20 against movement.

With these and other objects in view, the invention consists of certain novel features of construction, as will be more fully described, and particularly pointed out in the appended claims.

25 In the accompanying drawing:

Fig. 1 is a top plan view of the device assembled with ornamentation indicated thereon;

Fig. 2 is a bottom plan view thereof;

Fig. 3 is a rear view of the frame alone with 30 the locking member in section;

Fig. 4 is a rear view of the clip alone;

Fig. 5 is a central sectional view on line 5—5 of Fig. 1 of the parts assembled;

Fig. 6 is a sectional view of a fragmental portion of the frame on line 6—6 of Fig. 3;

Fig. 7 is a plan view thereof looking in the direction of the arrows 7 in Fig. 6;

Fig. 8 is a sectional view of the locking device.

In the use of separable articles of jewelry, particularly brooch clips, the separable articles to be used together must be attached in some convenient manner, and different ways have been provided which require that the size of the parts be of a certain definite proportion in order to lock 45 together; and it frequently occurs that various sizes are desired requiring for each size a complete set of parts, and in order to provide a single frame which will take all sizes, I have provided a locking arrangement enabling the clip to be placed upon the face of the frame centered with 50 reference thereto and locked in position without regard to the width of the ornament which may be mounted on the clip; and I have also arranged that the lock may be firmly held in either locked or released position, thus assuring that the lock 55

will be open when positioned on the frame to simplify the assembly of the parts; and the following is a more detailed description of the present embodiment of this invention, illustrating the preferred means by which these advantageous 5 results may be accomplished:

With reference to the drawing, 10 designates a frame which is of somewhat open work structure with piercings 11 and 12 to lighten its weight and provide in a general way ornamentation as 10 well as to provide certain functional parts. A pin 19 is hinged as at 20 on the frame and provided with a safety catch 21 for mounting the frame in position on the costume of the user. Arms 13 separated by a slit 14 extend longitudinally of the frame and there is provided between them an opening 15 following generally the configuration of a figure 8, having two generally arcuate portions 16 with a protuberance 17 between them. The frame also has raised projections 18 struck up from the stock serving as centralizing means, as will presently be described.

The clips which form the separate parts of the article of jewelry consist of a pair of ornaments 25 serving as front jaws with a back jaw 26 for 25 each ornament hinged to a mounting member portion 27 which is soldered to the ornament. The hinge connection comprises trunnions 28 on the back jaw fitting in ears 29 on the mounting member and provided with a spring 30 located 30 between the ears and engaging some flange or protuberance 31 on the back jaw for swinging the back jaw around the trunnions 28 as a pivot to closed position. The usual spurs 32 are provided on this back jaw to engage the garment 35 to which they may be attached, these clips being capable of separate use upon the costume.

The back jaws of each clip are each provided with cut-out formation 33 having a large opening 34 and smaller openings 35. The large opening 40 40 34 is surrounded by a circular portion 36 while the smaller openings are surrounded by circular portions 37 of the stock.

In assembling the two clips their back jaws are placed upon the front face of the frame which 45 is of such an arrangement that the protuberances 18 will extend into the openings 35 to positively position the back jaws on the frame and locate them in desired position longitudinally of the device, also centrally of the longitudinal line of 50 the device and usually with their straight edges 47 abutting. The width, however, of the clips is immaterial as they are positioned on the front face of the frame and there is nothing to interfere with or limit their extent laterally. 55

In order to secure the clips in position, a locking means comprising a stud member 38 having a head 39 and a shank portion 40 is slidably mounted on the frame. The head has beneath it a spacing shoulder 41 of the thickness of the frame 10 and a further reduction in size forms a slide portion 42 which fits within the slot 15. Upon the reduced shank 40 of the locking member, there is provided a head 43 which has a recess 44 flared to receive the headed over portion 45 of the shank. This head fits within the recess 44 so as to be substantially flush therewith and not protrude to catch in any of the clothing of the user. This stud may be moved in the slot 15 to either arcuate end thereof by snapping by the protuberance 17 by a flexing of the arms 13 so that the stud is locked at one or the other end of the slot.

When locked in released position by reason of its engaging the inner arcuate portion 16 of the slot 15 the locking member freely passes through the opening 34 in the back jaw of the clip at the time that the protuberances 18 enter the recesses or openings 35 of the clip, then by engaging the head 43 of the locking member and forcing it outwardly beyond the projection 17 which is permitted by the springing arms 13, the head 39 extends over the stock of the circular portion 36 to lock the clip firmly on the frame in assembled position, the portion 17 serving to retain it in this position until it is desired to release the members. For such release, the head 43 is again engaged and slid inwardly whereupon the parts may be separated or will fall apart if inverted, and the locking member will be positively held in position to again receive the clips when the parts are desired to be assembled.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An article of jewelry comprising separable members, cooperating means on said members to relatively locate the members, and locking means slidably carried by one of said members adapted for movement thereon to and from locking engagement with the other member to fasten said members together.

2. An article of jewelry comprising separable members, cooperating means on said members to relatively locate the members, locking means slidably carried by one of said members adapted for movement thereon to and from locking engagement with the other member to fasten said members together, and resilient means adapted to hold the locking means either in or out of locking position.

3. An article of jewelry comprising separable members, cooperating means on said members to relatively locate the members, a large opening in one member, a slot in the other member, a locking means slidably mounted in the slot on the other member having a head to extend through said opening and movable over the opposite surface of the member assembled thereon to lock the members together upon sliding movement of said locking means in said slot.

4. An article of jewelry comprising separable members, cooperating means on said members to relatively locate the members, a large open-

ing in one member, a slot in the other member, a locking means slidably mounted in the slot on the other member having a head to extend through said slot and movable over the opposite surface of the member assembled thereon to lock the members together upon sliding movement of said locking means in said slot, and resilient means adapted to hold the locking means either in or out of locking position.

5. A brooch clip comprising a frame member, a clip having a back jaw member engageable with the frame member, cooperating means on said members to relatively locate the members, locking means slidably carried by said frame member adapted for movement thereon to and from locking engagement with a portion of the clip member to releasably fasten the members together.

6. A brooch clip comprising a frame member, a clip having a back jaw member engageable with the front of the frame member, cooperating means on said members to relatively locate the members, comprising portions raised on one member and recesses in the other member to receive them, locking means slidably carried by said frame member adapted for movement thereon to and from locking engagement with a portion of the clip member to releasably fasten the members together.

7. A brooch clip comprising a slotted frame member, a clip having a back jaw member engageable with the frame member and provided with a large opening, cooperating means on said members to relatively locate the members, and a locking means slidably mounted in the slot in said frame member having a head to extend through said opening and movable over the opposite surface of the clip member assembled thereon to lock the members together upon sliding movement of said locking means in said slot.

8. A brooch clip comprising a frame member, a clip having a back jaw member engageable with the frame member, cooperating means on said members to relatively locate the members, locking means slidably carried by said frame member adapted for movement thereon to and from locking engagement with a portion of the other member to releasably fasten the members together, and resilient means to hold the locking means either in or out of locking position.

9. A brooch clip comprising a frame member, a clip having a back jaw member engageable with the front of the frame member, cooperating means on said members to relatively locate the members, comprising portions raised on one member and recesses in the other member to receive them, locking means slidably carried by said frame member adapted for movement thereon to and from locking engagement with a portion of the other member to releasably fasten the members together, and resilient means to hold the locking means either in or out of locking position.

10. A brooch clip comprising a slotted frame member, a clip having a back jaw member engageable with the frame member and provided with a large circular opening, cooperating means on said members to relatively locate the members, and a locking means slidably mounted in the slot in said frame member having a head to extend through said opening and movable over the opposite surface of the clip member assembled thereon to lock the members together upon sliding movement of said locking means to

one end of said slot, and resilient means to hold the locking means in locking position.

11. A brooch clip comprising a slotted frame member, a clip having a back jaw member engageable with the frame member and provided with a large circular opening, cooperating means on said members to relatively locate the members, a locking means slidably mounted in the slot in said frame member having a head to extend through said opening and movable over the opposite surface of the member assembled

thereon to lock the members together upon sliding movement of said locking means to one end of said slot, and resilient means to hold the locking means either in or out of locking position, said slot having arcuate end portions and a protuberance intermediate thereof whereby the locking means may be locked at one or the other end of the slot by snapping by said protuberance by a flexing of said resilient means. 5

JOHN FIELDING. 10
